[57] CLAIM

The ornamental design for a lighted walking cane, as
shown and described.

DESCRIPTION

FIG. 1 is a perspective view of a lighted walking cane
showing my new design;

FIG. 2 is a side elevational view thereof;

FIG. 3 is a front elevational view thereof, the rear being
a mirror image of the front shown in FIG. 3 with the
exception of the cane handle end edge;

FIG. 4 is a rear elevational view thereof;

FIG. 5 is a side elevational view thereof; and,

FIG. 5 is an exploded perspective view thereof.

FIG. 1

FIG. 2

FIG. 3

FIG. 4

FIG. 5
